VENETIAN BLIND HEAD BAR BRACKET

Julius Nisenson, Brooklyn, N. Y.

Application January 13, 1937, Serial No. 120,374

8 Claims. (Cl. 156—17)

This invention relates generally to brackets and more particularly to a bracket for supporting the head-bar of a Venetian blind.

An object of the present invention is the provision of a novel bracket structure which is completely reversible so that a single form of bracket may be used to support either end of the head-bar by merely reversing the position of the bracket.

Another object of the invention is the provision of novel structure whereby this improved bracket may be mounted on any one or more of three surfaces abutting the bracket.

Another object of this invention is the provision of single clamping means for detachably securing the head-bar in place regardless of the position of the bracket, that is, whether it is used on the left or right end of the head-bar.

A still further object herein is the provision of a Venetian blind head-bar bracket which is of substantially one piece construction, and which therefore may be easily and economically manufactured.

Another feature of the invention lies in the ease with which the bracket is installed, and the rapidity with which the head-bar may be positively secured or detached therefrom.

These objects and further features and advantages will more fully appear in the progress of this disclosure and as pointed out in the appended claims.

In the drawing forming a part of this disclosure, similar reference characters designate corresponding parts throughout the several views thereof.

Figure 1 is a fragmentary front elevational view of a preferred embodiment of the invention as used to support the left end of a Venetian blind head-bar.

Figure 2 is a view similar to Figure 1, but the bracket is shown in reversed position in order to support the right end of the head-bar.

Figure 3 is a side elevational view of the bracket as seen from the right of Figure 1.

Figure 4 is a plan view of the plane blank from which the bracket is formed.

Figure 5 is a perspective view, slightly reduced, of Figure 3.

Referring to Figures 3, 4, and 5, the bracket 10 is comprised generally of the side plate 11, including legs 12 and 13; head-bar supporting lugs 14 and 15; clamping screw supporting lug 16; and clamping and attaching lugs 17, 18, 19, and 20. The side plate 11 is substantially L shaped and the lugs 14 to 20 inclusive are all preferably integral with the side plate and bent up perpendicular therefrom.

The clamping screw support lug 16 is positioned at the juncture of the inner edges of legs 12 and 13 so that the principal surface of said

lug is at an angle of 45 degrees with relation to the inner edges of said legs adjacent thereto. Lug 16 is provided with a tapped hole 21 which threadedly carries a machine screw 22. Screw 22 is so positioned that the longitudinal axis 5 thereof bisects the right angle formed by legs 12 and 13.

The side plate 11 is preferably provided with a plurality of countersunk holes 23, 24, 25, 26, and 27. Holes 23 and 25 are preferably on a line parallel with the outer edge of leg 12, and holes 27 and 25 are preferably on a line parallel with the outer edge of leg 13, thus hole 25 is on a line with the longitudinal axis of screw 22. The holes 24 and 26 are preferably not on a line with their adjacent holes so that when the bracket is affixed to a wooden upright, the tendency of the wood to split is reduced.

The lugs 17, 18, 19, and 20 are preferably each provided with countersunk holes 28, 29, 30, and 31 respectively.

It may be noted at this point in the disclosure, that the leg 12 including its associated parts and orifices is symmetrical with relation to the leg 13 and its associated parts and orifices, and that this symmetry occurs at either side of an imaginary line passing through the longitudinal axis of the screw 22.

As seen in Figures 1 and 2, a door or window frame has vertical portions 32 and a horizontal portion 32' which face the ends and top respectively, of the Venetian blind head-bar 33. Numeral 34 indicates a wall, or window or door casement having a front surface which faces the rear side of the head-bar 33. A slat tilt bar 35 is supported from the undersurface of head-bar 33 by any suitable means such as brackets 36, and the tilt bar in turn supports slat carrying tapes 37. The slat tilt bar and its related structure is not shown or described in any particular detail 30 because the head-bar 33 may be used to support any known slat tilting or elevating mechanism and the present application is directed to the head-bar supporting bracket.

Turning to Figure 1, where the bracket 10 is used to support the left end 38 of the head-bar 33, leg 12 is placed uppermost, and in a horizontal position, while leg 13 is in a vertical position and to the rear. The smooth side of bracket 10 is placed against the vertical portion 32. It 50 then becomes a matter of choice with the person installing the bracket as to which of the holes, 23 to 31, inclusive, shall be penetrated by screws to thereby support and attach the bracket. Factors which will affect this choice will be: the total 55 weight of the Venetian blind carried by the head-bar; whether or not there are, in the particular installation, surfaces corresponding to portions 32, 32', or the surface indicated by numeral 34; and what is the particular character of said sur- 60

faces. It may thus be seen that this improved bracket is readily adapted to many different conditions of special and usual installations. It is obvious that various types of screws or nails may be used to secure the brackets in place—such as "wood" screws, machine screws (in tapped orifices), or self tapping screws. Flat headed screws are preferable so that in conjunction with the countersunk holes a flush surface is produced and the head-bar may be slid freely into and out of position on the bracket.

When the bracket 10 is placed in the position just described, the lug 14 supports the head-bar end 38 in conjunction with the upper end of the screw 22. This support of the head-bar end is diagrammatically illustrated in Figure 3 wherein the head-bar outline is shown in dot-dash lines, and the advanced position of the screw end is shown in dash-double-dot lines. The screw 22 in cooperation with the lugs 17, 18, and 19 forms a clamping device which securely seats the head bar in place in the bracket and aligns it in contact with the inner face of the lugs 18 and 19. Thus the lugs 17, 18, and 19 perform a double function as cooperating mechanism for the clamping screw 22 and as attaching means for the supporting of the bracket. By reason of the fact that the screw 22 approaches the under surface of the head-bar at an angle of 45 degrees, the screw can cut into the head-bar and can force it in a direction having upward and rearward components. Manipulation of the screw 22 is obtained with an ordinary screw driver, but it shall not be considered to be beyond the scope of this invention to substitute a winged, or knurled head for the slotted head of said screw.

Turning to Figure 2, the bracket 10 is shown as used to support the right end 39 of the head-bar 33. Here leg 13 is placed uppermost, and in a horizontal position, while the leg 12 is in a vertical position and to the rear. The bracket 10 now functions exactly as it does when used to support the left end 38 of the head-bar. The various parts are reversed, however. Lug 15 in conjunction with screw 22 now supports the head-bar end, and screw 22 forces the head-bar toward lugs 18, 19, and 20.

It may now be seen that there has been provided an improved Venetian blind head-bar supporting bracket which satisfies the objects set forth hereinabove.

The foregoing description has been made rather detailed for clearness of understanding only, and no unnecessary limitations should be understood therefrom, but the appended claims should be construed as broadly as permissible in view of the prior art.

I claim:

1. A reversible Venetian blind head-bar supporting bracket including a pair of spaced clamping and attaching lugs, oppositely disposed and forming an angle with relation to each other; clamping means, adapted for rectilinear movement in a direction which bisects the angle formed by said clamping and attaching lugs; and a pair of head-bar supporting lugs, one of said head-bar supporting lugs being parallel to and spaced from one of the said attaching lugs, and the other one of said supporting lugs being parallel to and spaced from the other attaching lug.
2. A Venetian blind head-bar supporting bracket having clamping means adapted for rectilinear

movement toward or away from a head-bar placed in said bracket and adapted to engage the same, the direction of said movement being less than 90 degrees with relation to the under horizontal surface of said head bar.

3. In a Venetian blind head-bar supporting bracket for use in conjunction with a head-bar substantially rectangular in cross section, a lug adapted to support the under surface of said head-bar placed in said bracket, and clamping means adapted for rectilinear movement toward or away from said under surface, the direction of said movement being at an angle of less than 90 degrees with relation to said under surface.

4. In a Venetian blind head-bar supporting bracket for use in conjunction with a head-bar substantially rectangular in cross section, a lug adapted to contact the upper surface of said head-bar placed in said bracket, and clamping means adapted for rectilinear movement toward or away from the under surface of the head-bar, the direction of said movement being at an angle of less than 90 degrees with relation to said undersurface.

5. In a Venetian blind head-bar supporting bracket for use in conjunction with a head-bar substantially rectangular in cross section, a lug adapted to support the upper surface of said head-bar placed in said bracket, said lug having an orifice therein whereby said lug may be attached to an abutting surface by means of a screw, and clamping means adapted for rectilinear movement toward or away from said under surface, the direction of said movement being at an angle of less than 90 degrees with relation to said under surface.

6. In a Venetian blind head-bar supporting bracket for use in connection with a head-bar substantially rectangular in cross section, a pair of lugs adapted to contact the upper and rear surfaces respectively, of a head bar placed in said bracket, said lugs forming an angle of 90 degrees with respect to each other, and clamping means adapted for rectilinear movement toward or away from the under surface of said head-bar, said movement being in a direction bisecting the angle formed by the said lugs.

7. In a Venetian blind head-bar supporting bracket for use in connection with a head-bar substantially rectangular in cross section, a pair of lugs adapted to contact the upper and rear surfaces respectively, of a head-bar placed in said bracket, said lugs forming an angle with respect to each other, and clamping means adapted for rectilinear movement toward or away from the under surface of said head bar, said movement being in a direction bisecting the angle formed by said lugs.

8. In a Venetian blind head-bar supporting bracket for use in connection with a head-bar substantially rectangular in cross section, a pair of lugs adapted to contact the upper and rear surfaces respectively, of a head bar placed in said bracket, said lugs forming an angle with respect to each other, clamping means adapted for rectilinear movement toward or away from the under surface of said head-bar, said movement being in a direction bisecting the angle formed by said lugs, and another lug adapted to support the surface of said head bar from underneath same.

JULIUS NISENSON.
